FOLDING DECK STOCK CAR

Filed Feb. 25, 1928

UNITED STATES PATENT OFFICE

ARTHUR R. BURKE, OF ROCHESTER, MINNESOTA

FOLDING DECK STOCK CAR

Application filed February 25, 1928. Serial No. 256,948.

My invention relates to improvements in folding deck stock cars, and it consists in the combinations, constructions, and arrangements herein described and claimed.

An object of my invention is to provide a folding deck stock car wherein a novel means is provided for supplying an additional deck for a stock car.

A further object of my invention is to provide a device of the type described in which a portion of the deck may be used for stock and the other portion of the deck may be employed for receiving and retaining feed for the stock.

15 A further object of my invention is to supply a stock car of ordinary construction with a double deck or floor and to so construct this deck or floor that it may be extended to an operative position or folded against the sides or roof of the car, so as to enable the car to be used without the upper deck or floor, and at the same time when upper decks or floors are folded to lower sides of car, they are in position for easy cleaning.

20 A further object of my invention is to provide a device of the type described which provides a shielding means for the animals when in one position.

Other objects and advantages will appear 25 in the following specification, and the novel features of the invention will be particularly pointed out in the appended claims.

My invention is illustrated in the accompanying drawings, forming part of this application, in which

Figure 1 is a longitudinal sectional view taken substantially along the line 1—1 of Figure 2,

Figure 2 is a cross section taken substantially along the line 2—2 of Figure 1,

Figures 3, 4, 5, and 6 are diagrammatic illustrations of the device illustrating the deck in various positions,

Figure 7 is a detailed view of a portion of my device, and

Figure 8 is a fragmentary view of a portion of my device.

In carrying out my invention, I provide a body portion 1 having side walls 2 and 3, a floor 4, and a top 5. The walls 2 and 3 are

provided with spaced-apart slats 6, as is the custom in stock cars, for providing the proper ventilation. Beams 7 are disposed at spaced-apart positions upon the side walls 2 and 3 for supporting the top 5.

Three sections; i. e., end sections A and B, and a central section C, are provided. The end sections A and B are substantially identical in construction and are provided with movable portions 8 and 9, and 10 and 11, respectively. The central section C is provided with movable portions 12 and 13.

The portions 8 to 13, inclusive, are all provided with reinforcing strips 14 having elongated slots 15 in the outer ends thereof. A 65 plurality of supporting bars 16 is provided for the portions 8 and 9 of the section A.

A plurality of supporting bars 17 is provided for the portions 12 and 13 of the section C, and a plurality of supporting bars 70 18 is provided for the portions 10 and 11 of the section B. The bars 16, 17, and 18 are identical in construction—therefore, a description of one will apply to them all. For

example, by viewing Figure 2, it will be noted 75 that the bars are provided with horizontal rest portions 19 which extend through the side walls and are rigidly secured thereto. Vertical guide portions 20 extend upwardly from the rest portion. At the upper extremity of the rest portion, the supporting bar is formed into a retaining eyelet 21. From the eyelet 21, the supporting bar extends in a horizontal direction and is rigidly secured to the side wall, as shown.

The supporting bars 16, 17, and 18 extend 80 through the elongated openings in the reinforcing strips and in this manner the portions of the sections A, B, and C are substantially hinged to the supporting bars. The inner 85 edges of the portions of the sections A, B, and C are provided with retaining rings or eyelets 22 which are arranged to receive hooks

23 carried by chains 24. The opposite ends of the chains 24 are supported by means of 90 brackets 25 which are rigidly secured to the beams 7.

From the foregoing description of the various parts of the device, the operation thereof 95 may be readily understood. It may be ob-

served by viewing Figures 1 and 2 that the portions of the sections A, B, and C may be disposed in the position parallel with the floor 4. While in this position, the portions of the sections A, B, and C are supported at their outer edges by the portions 19 of the supporting bars. The portions of the sections A and B are supported at their inner edges by the chains 24. The portions 12 and 13 of the section C are provided with sliding latches 26 which are arranged to be moved outwardly into engagement with the upper surfaces of the portions of the sections A and B. In this manner, the additional deck 15 is provided for smaller animals, such as hogs or sheep. The portion 12 of the section C may be lowered or raised, if desired, for aiding in the loading of the stock. The same is true of the portion 13.

20 The portions of any one or all of the sections may be released by removing the hooks 23 from the eyelets 22 and allowing the portions to swing downwardly and assume a position adjacent the side walls 2 and 3. 25 In this manner, the stock, when only the lower deck is used, is protected against the wind or weather. This is illustrated in Figure 3.

Furthermore, one or more of the sections 30 A, B, and C may be used for stock and the remaining section or sections may be used for receiving and retaining feed for the stock. When this is desired, the section for receiving and retaining the feed is placed in the 35 position illustrated in Figure 5. It will be observed that the outer edges of the portions are moved upwardly until the outer ends of the reinforcing strips have been received in the retaining eyelets 21. When the portions 40 are disposed in this position, they are in the form of a trough and may receive and retain any desired grain or feed.

Any or all of the portions of the sections A, B, and C may be disposed in the positions 45 illustrated in Figure 4; i. e., the outer ends supported by the supporting eyelets 21 and allowed to suspend from these eyelets in vertical positions. When the portions are in this position, the stock will be protected 50 against the sun's rays. While the portions are in the positions illustrated in Figures 3 and 4, the free ends of the chains 24 may be attached to hooks 27 which are carried by the beams 7.

55 It is obvious by viewing Figure 6 that the portions of any one or all of the sections A, B, and C may have their inner edges secured to the beams 7 while their outer edges are supported by the supporting eyelets 21.

60 I claim:

1. The combination of a car having side walls, a floor, and a top, spaced-apart supporting bars rigidly carried by the side walls, a deck comprising a pair of sections movably connected with said supporting bars,

one of the sections being connected with the bars upon one side of the car and movable independently with respect to the section movably carried by the bars upon the opposite side, each of said bars being spaced away 70 from the walls of the car and provided with a loop portion extending inwardly with respect to the car, said sections being arranged to be moved to depending positions from the lower ends of the bars or the loop portions, 75 said sections being further arranged to be moved to inclined depending positions from the loop portions and connected together, said sections being further permitted to be placed substantially adjacent the top of the 80 car while connected with the loop portions, and means cooperating with said bars whereby the sections may be supported in a plane parallel with the floor of the car.

2. The combination of a car having side 85 walls, a floor, and a top, spaced-apart supporting bars rigidly carried by the side walls, a deck comprising a pair of sections movably connected with said supporting bars, one of the sections being connected with the 90 bars upon one side of the car and movable independently with respect to the section movably carried by the bars upon the opposite side, each of said bars being spaced away 95 from the walls of the car and provided with a loop portion extending inwardly with respect to the car, said sections being arranged to be moved to depending positions from the lower ends of the bars or the loop portions, 100 said sections being further arranged to be moved to inclined depending positions from the loop portions and connected together, said sections being further permitted to be placed substantially adjacent the top of the 105 car while connected with the loop portions, and means cooperating with said bars whereby the sections may be supported in a plane parallel with the floor of the car, said sections being provided with reinforcing strips 110 having openings for receiving said bars.

Signed at Rochester in the county of Olmsted and State of Minnesota, this 21st day of February, A. D. 1928.

ARTHUR R. BURKE.
